UNITED STATES PATENT OFFICE.

LOUIS JOS. BRUNE, OF ALGIERS, LOUISIANA.

CLASP-HOLDER FOR IRONS.

1,216,653.

Specification of Letters Patent. Patented Feb. 20, 1917.

Application filed October 21, 1916. Serial No. 186,933.

To all whom it may concern:

Be it known that I, Louis Jos. BRUNE, a citizen of the United States, residing at Algiers, in the parish of Orleans, State of Louisiana, have invented a new and useful Clasp-Holder for Irons; and I do hereby declare the following to be a full, clear, and exact description of the invention, such as will enable others skilled in the art to which it appertains to make and use the same.

The present invention relates to a clasp holder for flat irons, and has for its object to provide a device of this character which embodies novel features of construction whereby it can be readily applied to or removed from the handle of an ordinary flat iron, and will enable the flat iron to be handled without the use of a rag or cloth holder, and without danger of burning the hands.

Further objects of the invention are to provide a flat iron holder which is simple and inexpensive in its construction, which can be almost instantly applied to or removed from the handle of any conventional flat iron, and which enables a hot flat iron to be handled without burning the fingers.

With these and other objects in view, the invention consists in certain novel combinations and arrangements of the parts as will more fully appear as the description proceeds; the novel features thereof being pointed out in the appended claims.

For a full understanding of the invention, reference is to be had to the following description and accompanying drawings, in which:

Figure 1 is a side elevation of a flat iron provided with a holder constructed in accordance with the invention.

Fig. 2 is an enlarged transverse sectional view through the clasp holder and flat iron handle, said view being taken on the line 2—2 of Fig. 1.

Fig. 3 is a similar view on the line 3—3 of Fig. 1.

Fig. 4 is a detail view of the clasp holder, the two halves thereof shown as swung apart into an open position.

Corresponding and like parts are referred to in the following description and indicated in all the views of the drawings by the same reference characters.

For the purpose of illustration, the holder is shown as applied to the handle 1 of an ordinary flat iron 2, the upper portion of

the handle being enlarged at 1^a in the usual manner to provide a hand hold which can be more readily grasped by the hand. Ordinarily, rag and cloth holders are used when grasping the handle of the flat iron in order to prevent burning of the hands, and the object of the present invention is to provide a neat and compact holder which will take the place of the rag and cloth holders, and which can be almost instantly fitted upon the flat iron handle or removed therefrom.

The holder may be conveniently formed of wood or other suitable insulating material, and is constructed in two similar and complementary halves 3, said halves being of an elongated formation, and being recessed at 4 to receive the enlarged portion 1^a of the flat iron handle 1. Reduced necks 5 lead from the ends of the recesses 4 through the ends of the halves 3 of the holder, said necks being angularly disposed and being adapted to receive the reduced end portions of the handle 1 in such a manner as to interlock therewith and prevent bodily rotation of the holder upon the handle. The two halves 3 of the holder are hingedly connected with each other at their upper edges, as indicated at 6, said upper edges being also correspondingly recessed to provide a pocket 7 within which a coil spring 8 is housed, the respective extremities of the said spring being extended laterally at 8^a and secured to the halves 3 of the holder so that the tension in the spring normally tends to swing the halves of the holder into an open position.

The swinging edge of one of the halves 3 is provided with a latch plate 9, while the nose 10^a of a spring latch member 10 projects from the swinging edge of the opposite half 3, said nose being adapted to engage the latch plate to lock the two halves of the holder securely together when they are forcibly closed. The spring latch member 10 is suitably let into the member 3 so as not to interfere with the smooth exterior surface of the latter, and a button 11 which projects from the spring latch member terminates flush with the surface of the member 3, so that it does not project outwardly therefrom, although it can be readily forced inwardly by the pressure of one of the fingers. When this button is thus forced inwardly the nose 10^a of the spring latch member 10 is disengaged from the latch

plate 9 and the two halves 3 of the holder swung into an open position by the action of the spring 8.

If desired, the recesses 4 may be lined 5 with asbestos or like material, as indicated at 12, and corrugated spring plates 13 may be arranged over the lining in such a manner as to yieldably engage the enlarged portion 1^a of the flat iron handle 1 to take up 10 any looseness which would otherwise be present. The flat iron handle is thus securely gripped in such a manner that it can be easily handled without danger of burning the hands. The holder is locked against 15 bodily rotation upon the flat iron handle when in position thereon, and it can be almost instantly clasped upon the handle, or removed therefrom by pressing upwardly upon the button 11.

Having thus described the invention, 20 what I claim as new and desire to secure by Letters-Patent, is:—

1. A clasp holder for flat iron handles, including a pair of complemental halves 25 hingedly connected at one of their edges and correspondingly recessed on their inner

faces to receive the flat iron handle, corrugated spring plates within the recesses for positively gripping the flat iron handle, and latch means for locking the two complemental halves in a closed position. 30

2. A clasp holder for flat iron handles, including a pair of complemental halves hingedly connected at one of their edges and correspondingly recessed in their inner faces 35 to receive the enlarged hand hold of a flat iron handle, reduced necks being provided at the ends of the recesses for receiving the reduced portions of the flat iron handle, corrugated spring plates extending around the 40 bases of the recesses for positively gripping the flat iron handle, and latch means for locking the two complemental halves in a closed position.

In testimony whereof I have signed my 45 name to this specification in the presence of two subscribing witnesses.

LOUIS JOS. BRUNE.
